UNITED STATES PATENT OFFICE.

GOTTLIEB MEYFARTH, OF GENEVA, SWITZERLAND, ASSIGNOR OF ONE-HALF TO THE FIRM: SOCIÉTÉ ANONYME DES ATELIERS DE SÉCHERON, OF SECHERON, GENEVA, SWITZERLAND, A CORPORATION OF SWITZERLAND.

CUT-OUT DEVICE FOR PNEUMATICALLY-OPERATED SWITCHES.

Application filed November 4, 1924, Serial No. 747,712, and in Switzerland November 22, 1923.

This invention relates to a cut-out device for mechanical control-gears of groups of pneumatically operated single switches, more particularly for electric vehicles.

5 These control gears, more particularly for electric vehicles, have the practical disadvantage, similar to all hand control gears, that they cannot be switched off suddenly as the zero position is obtained only by moving back over the previous contact steps. The driver of an electric vehicle may of course switch off the main switch but this is very undesirable as in that way all the auxiliary machinery on the vehicle is put 10 out of action at the same time. The said disadvantage is obviated according to the present invention by so arranging the cut off device, that it effects the sudden cutting or switching out of the single switches 15 closed in any running position and that the action of the mechanical drive on the control of the single switches remains suspended until it is brought into the zero position.

Several constructions of the cut-off device according to the invention are illustrated by way of example in the accompanying drawings in which:

Figures 1 and 2 show a control provided with a first construction,
30 Figures 3 and 4 relate to a control fitted with a second construction,
Figures 5 to 8 show a control in which is used another construction,
Figures 9 to 12 show a control in which is used a fourth construction, and
Figure 13 relates to a last construction.

Figure 1 shows a group of three single switches 1, 2, 3 which belong to a vehicle control for single phase current, the contacts 40 of which on one side are connected to various tappings of the secondary winding of a step transformer not shown, and on the other side feed the motors. The contacts 16 are operated by means of a rod 17 which is moved, for closing the said contacts, by a piston 14 travelling in a compressed air cylinder 13, and for opening, by a spring 15. The air admission to, and discharge from, the cylinder 13 is controlled by two valves 11, 12 mounted on one and the same rod 10 provided with a roller. The rollers of 45 all the rods 10 are operated by a travelling

nut or carriage 7 mounted on a spindle. The latter is rotated by hand by means of two chain wheels, chain 5 and hand wheel 55 20 on the controller 4. The nut 7 is provided with a switching cam 8 which contacts with all the rollers of the rods 10, and with two locking lugs 9 co-operating with locking rods 19 provided for each single switch 60 1, 2, 3; the locking rods 19 are operated through levers 18 by the rods 17.

The switching cam 8 is not secured rigidly to the nut 7; it can move up and down transversely of the spindle 6, as it is provided 65 with two guide parts 8¹, 8² engaging with corresponding openings in the nut 7. Normally it is held raised by springs 27, but it may also be pulled down by a horizontal rod 24 which co-operates with rollers 26 70 provided on the guide parts 8¹, 8². The rod 24 is pivoted at both ends to arms 22, 23 rotatable about horizontal pins arranged transversely of the rod. The rod 24 can therefore be raised or lowered by the rotation of the arms. The rotation of the arms in the direction of lowering the rod 24 is brought about by a switching out lever 21 provided on the controller 4 of the vehicle and connected by a rod 25 to a second arm 80 22¹ secured to the arm 22. The rotation in the opposite direction is produced by a third arm 22² also secured to the arm 22, against which the nut 7 strikes. The arm 22¹ is further provided with a pin 23¹ which moves 85 in a slot 28 of the rod 25.

The working of this control device and of the construction of the cut-off device with which it is provided, is as follows:

In Figure 1, the rods 10 of the valves 11, 12 of the two single switches 1, 2, have met the adjustable cam 8, which is pressed upwardly by the springs 27 as the rod 24 is in the raised position; the single switches 1, 2 are closed, whilst the single switch 3 is open. If the closed single switches 1, 2 are to be suddenly opened, the switching out lever 21 must be pulled. In that way the cut-out rod 24 is moved in the direction of the arrow and brought into the position shown in Figure 2. Owing to the movement of the cut out rod 24, the cam 8 will be moved downwards against the action of the springs 27 by means of the driving

rollers 26, and lifted off from the rods 10 of the single switches 1 and 2, which will at once result in cutting out or opening the single switches 1 and 2.

5 When the switching or cut-out device has been once operated, no single switch can be closed again until the nut 7 has been brought to the zero position by means of the hand wheel 20. This is attained owing to the 10 fact that the switching out rod 24 once brought by the switching out lever 21 into the switching out position shown in Figure 2, can no longer be moved back on account of the slot 28 in the driving rod 25, and also 15 owing to the fact that the nut 7, during its last return to the zero position, moves back the arm 22 and with it the switching out rod 24, the cam 8 being brought to the normal position by the action of the two springs 20 27.

In the second construction of the cut-out device (Figures 3 and 4), the operation of the same is effected by means of the same part—hand wheel 20—as that for the single switches 1, 2, 3.

The cam 8 of the nut 7 may be locked in its lower position by means of a lock 31 which is controlled by the action of a spring 33, but may be held by a pawl 30 in such 30 a position that the cam 8 is in its raised position. The pawl 30 is pivoted to an arm of a T-shaped releasing lever 29; a spring 35 acts on another arm of the lever, whilst the third arm may be operated by the locking rods 19 of the single switches.

The working of the second construction is as follows:

In Figure 3, the valve-operating rods 10 of the single switches 1 and 2 have met the 40 cam 8 which is in its raised position and therefore have closed the single switches 1 and 2 whilst the single switch 3 is open.

If in this case the single switches 1 and 2 are to be suddenly opened or switched off, 45 the hand wheel 20 of the controller 4 must be turned to one contact step in the direction of switching off, namely this turning must be effected more quickly than in the case of normal switching. In that way the nut 7 is moved so quickly in the direction of the arrow in Figure 3 that the releasing lever 29 mounted on it, is turned by the locking rod 19 of the single switch 2 before the single switch 2 had time to cut out or open.

Owing to the said turning, the pawl 30 connected to the releasing lever 29 disengages the lock 31, and the latter is moved into the position shown in Figure 4. Owing 55 to this movement of the lock 31, the driving rollers 26 of the cam 8 engage with the cams 32 of the lock 31, owing to which the cam 8 is moved away from the rods 10 of the single switches 1 and 2, which brings about an immediate opening of the latter.

60 When the cut-out device has once acted,

no single switch can be closed again, until the nut 7 has been brought to the zero position by means of the hand wheel 20.

Only during the last return movement of the nut 7 to the zero position, the lock 31 70 is moved back by a fixed stop 34 and locked by the pawl 30 controlled by the spring 35. At the same time the disengaged cams of the lock 31 enable the cam 8 to return to the normal position under the action of the two 75 set springs 27, and the control device is again ready for switching in.

When a control device which is on any contact step, is to be moved back only to the extent of one or more steps, the driver 80 must turn back the hand wheel 20 with normal speed; the cut-out device does not then become operative. Owing to the slower movement of the nut, the single switch to be opened, operated by the rod 10 meeting the 85 cam 8, has sufficient time to complete its opening movement, and therefor also to complete the return of the locking rod 19, so that the pawl lever 29 does not strike the latter, 90 the release of the cam thus being avoided.

According to Figures 5-8, the operation of the air valves 11, 12 of the single switches 1, 2, 3 is effected by means of a cam shaft 39 operated by the hand wheel 20 of the controller 4 by means of a chain 5 and gear 95 wheels 36, 37. A subsequent locking of the cam shaft 39 in the case of a wrong position of the contacts 16 (Figure 1) is effected by means of a locking rim 40 provided on each cam disc, in such a manner that a locking pawl 42 operated by means of a lever 18 and a connecting rod 41 from the piston rod 17, engages with the locking rim 40 and prevents any further switching.

The working of the third construction is 105 as follows:

Figures 5 and 6 show the rollers of the rods 10 of the single switches 2, 3 in engagement with the cam discs 38, so that the contacts 16 of the said single switches 2, 3 are 110 closed, whilst the single switch 1 is open.

If in the present case the single switches 2 and 3 are to be suddenly opened, the switching out lever 21 must be pulled over, owing to which the cam shaft 39 with the driver 115 collars 43 is moved by the driving rod 25, by means of bell crank levers 44, in the direction of the arrow to such an extent that the rods 10 of the single switches 2 and 3 are laterally moved away from their cam 120 discs as shown in Figures 7 and 8, which results at once in the opening of the two single switches 2, 3.

When the cut-out device has been once operated, no single switch may be closed 125 again until the cam shaft 39 has been brought to the zero position. This is attained owing to the fact that the cam shaft, once brought by the switching out lever 21 into the switching off position Figure 8, is no longer 130

6 moved back owing to the existence of the slot 28 in the driving rod 25, and that also the cam shaft 39, during its last return movement to the zero position, is pushed into its
 5 normal position by the cam 46 of the gear wheel 37 and by the fixed cam 45, owing to which the control device is again made ready for switching.

If, after the cut-out device has been
 10 operated, a single switch does not open for some reason, that is to say if the locking lever of the corresponding switch remained in the position shown in Figure 5, the locking rim 40 strikes the locking lever in
 15 question during the turning back of the cam shaft 39, and the driver of the car is prevented from moving the cam shaft 39 back to the zero position, that is to say prevented from closing any single switch.

20 In the fourth construction (Figures 9-12) the sudden opening of the single switches is effected, as in the second construction, by a quick turning back of the hand wheel 20.

In Figure 10, the rods 10 of the single switches 2 and 3 have met the cam discs 38, so that the single switches 2 and 3 are closed, and the single switch 1 is open. If in this case the single switches 2 and 3 are to be suddenly opened, the hand wheel 20 of the controller 4 must be quickly turned to the extent of one contact step in the direction of opening. Owing to this quicker turning of the cam shaft 39, the bevelled locking rim 40 of the single switch 3 comes in contact, before the switch had time to open, with the bevelled locking lever 42 of the same switch, owing to which the cam shaft 39 is moved in the direction of the arrow to such an extent that the rods 10 of the single switches 2 and 3 are disengaged laterally from their cam discs 38 as shown in Figure 12, which results in an immediate opening of the two single switches.

45 After the switching out device has acted, no single switch can be closed again—as in the preceding constructions—until the cam shaft 39 has been brought to the zero position. Only in the last return movement of the cam shaft 39 to the zero position, the said shaft will be pushed into the normal position by the cam 46 of the gear wheel 37, and the fixed cam 45, and in that way the control gear is again made ready for switching.

55 If the driver of the car wishes to switch back the control device of groups of single switches, which is in any switching position, to the extent of one or more steps he must turn the hand wheel 20 with normal speed
 60 in the direction of switching out. The switching out device does not then become operative. Owing to the slower turning of the cam discs 38, the single switch to be opened, operated by the rod 10 meeting the cam disc 38, has sufficient time to complete

its switching out movement, and therefore also to complete the return of the locking lever 42, so that the bevelled locking rim 40 does not come in contact with the latter and therefore the cam shaft 39 is not moved. 70

Figure 13 shows the last construction in which the cutting out of the single switches, and the rendering inoperative of the mechanical drive are effected by the first turning of the switching out lever 21 on the controller 4; the further turning of the said switching out lever 21 brings to the zero position the drive of the control device of the mechanical-pneumatic single switches, which drive may be in any switching position, 80 that is to say it is no longer possible to effect the return of the mechanical drive to the zero position by means of the hand wheel 20.

A sudden opening of the single switches which may be in any switching position, and 85 the putting back of the mechanical drive, are effected as follows:

By pulling over the switching out lever 21, during the first turning, the cam shaft 39 is moved, by means of an intermediate 90 lever 48 connected to the lever 21 by means of a ball 47, and by means of the driving rod 25, bell crank lever 44 and driving collars 43, to such an extent that the rods 10 of the closed single switches move laterally off the 95 cam discs 38, which results in an immediate opening of the corresponding single switches. In the first turning of the switching out lever 21, the hand wheel 20 is also uncoupled by means of a claw coupling 50 operated by 100 means of a rod 49, and held fast. The continued turning of the switching out lever 21 will turn in the direction of the arrow a gear wheel 51 which has engaged with it, and in that way returns to the zero position 105 the single switch drive by means of a gear wheel 52 provided on a spindle 53. The intermediate lever 48 (and with it the whole cut-out device) which during the first turning movement came in contact with the cam 54, remains stationary as during further turning it will be disconnected from the switching out lever 21.

110 After the single switches have been opened by the first turning movement of the switching out lever 21, none of them can be again closed until the second turning movement of the switching lever has been effected, that is to say until the cam shaft 39 has been brought back to the zero position. 115 This is attained owing to the fact that the cam shaft 39, moved into the switching out position by the first turning of the switching out lever 21, is no longer moved back on account of the slot 28 in the driving rod 25, and that also the cam shaft 39, in its last return movement to the zero position, is pushed into the normal position by the cam 46 of the gear wheel 37 and the fixed cam 45. 120 125 130

Only by returning the switching out lever 21 to the normal position, the hand wheel 20 is again unlocked by the claw coupling 50 and in that way the control device rendered again ready for switching.

Obviously, in place of hand drive for the control device by means of the hand wheel 20, a servomotor may be used, for instance an electric motor or a driving apparatus operated by compressed air. Cam shaft 39 may also be axially displaced by pneumatic or electric devices.

The number of the single switches in the group may of course be otherwise than 15 three. The current controlled by the said single switches may be a different one from single phase current; although the control devices to which the cut-out device is fitted, are chiefly intended for electric vehicles, 20 they may be used for other purposes.

What I claim is:

1. In an apparatus of the class described, a plurality of control members, a movable carriage, a cam associated with the carriage and adapted to actuate the said control devices, means for operating the cam to release a plurality of said control devices, and means whereby the said cam remains inoperative until the said carriage is returned to an initial position.
2. In an apparatus of the class described, a plurality of control members, a movable carriage, a cam associated with the carriage, means for normally maintaining the cam in an operative position for actuating the said control devices, means for shifting the cam to an inoperative position to simultaneously release a plurality of the said control devices, and means whereby 40 when so actuated the cam remains inoperative until the carriage is returned to an initial position.
3. In an apparatus of the class described, a plurality of control members, a movable carriage, a cam associated with the said carriage, yielding devices for normally maintaining the said cam in a raised position to actuate the said control devices, a rod cooperating with the said cam, means for actuating the rod to move the cam against the action of the said yielding devices to thereby render the cam inoperative and to release the said control devices, and means whereby when thus rendered inoperative the cam remains inoperative until the carriage is returned to an initial position.

4. In an apparatus of the class described, a plurality of control members, a movable carriage, a cam associated with the said carriage, yielding devices for normally maintaining the said cam in a raised position to actuate the said control devices, a rod cooperating with the said cam, rocker arms to which the said rod at the ends thereof is pivotally connected, means for swinging one of the said arms to actuate the rod and to move the cam against the action of the said yielding devices to an inoperative position to thereby release the said control devices, and means whereby the cam remains in an inoperative position until the said carriage is returned to an initial position.

5. In an apparatus of the class described, a plurality of control members, a movable carriage, a cam associated with the said carriage, yielding devices for normally maintaining the said cam in a raised position to actuate the said control devices, a rod, rocker arms to which the ends of the said rod are pivotally connected, a link connected to one of the rocker arms with a slip movement, means for actuating the said link to swing the said rocker arm and to thereby shift the cam to an inoperative position, and an extension carried by the aforesaid rocker arm actuated by the link with which the said carriage in an initial position is adapted to contact to swing the rocker arm to reset the said rod and cam.

6. In an apparatus of the class described, a plurality of control members, a movable carriage, a cam associated with the said carriage, yielding devices for normally maintaining the said cam in a raised position to actuate the said control devices, a rod, rocker arms to which the ends of the said rod are pivotally connected, a link connected to one of the rocker arms with a slip movement, a lever for actuating the said link to swing the said rocker arm and to thereby shift the cam to an inoperative position, an extension carried by the aforesaid rocker arm actuated by the link with which the said carriage in an initial position is adapted to contact to swing the rocker arm to reset the said rod and cam, and means for moving the said carriage.

In testimony whereof I have affixed my signature.

GOTTLIEB MEYFARTH.
